UNITED STATES PATENT OFFICE.

FRANCIS E. STEVENSON, OF MOUNT GILEAD, OHIO, ASSIGNOR TO THE HYDRAULIC PRESS MANUFACTURING COMPANY, OF MOUNT GILEAD, OHIO, A CORPORATION OF OHIO.

EXTRUSION-PRESS.

1,335,466.

Specification of Letters Patent. Patented Mar. 30, 1920.

Application filed September 2, 1919. Serial No. 321,080.

To all whom it may concern:

Be it known that I, FRANCIS E. STEVENSON, a citizen of the United States, residing at Mount Gilead, in the county of Morrow and

5 State of Ohio, have invented certain new and useful Improvements in Extrusion-Presses, of which the following is a specification.

This invention relates to apparatus for 10 producing from masses of plastic material strips or ribbons of such material, and particularly to presses operated by hydraulic pressure for producing such strips or ribbons from plastic material such as asphalt.

15 Flat strips of asphalt are largely used for expansion joints in concrete roads, sidewalks, and in buildings for preventing the cracking or breaking of the concrete. Such strips have heretofore commonly been made 20 by passing the material through rolls and then slitting the sheets thus produced to provide strips of the desired width and thickness. Ordinarily the asphalt is first melted and poured into pans which have 25 been previously coated or prepared in such manner as to prevent the material from sticking to the pans. When cool the material is emptied from the pans and placed in a tempering bath of warm water, after 30 which it is rolled and divided in the manner before explained.

I have found that these operations may be performed in a much simpler way.

According to my invention, the asphalt 35 is removed from the containers by cutting and stripping off the metal sheath or casing and is then rolled into a press which is provided with a plunger operated by compressed air which forces the cylindrical 40 mass of material into the chamber of the press. The press plunger or ram is then moved into line with the material and hydraulic pressure is applied for forcing the material out through suitable dies in the 45 form of a ribbon or strip of the desired size. The die is made in adjustable sections by means of which the width and thickness of the strip may be varied at will.

In the accompanying drawings:—

50 Figure 1 shows a side elevation of an extrusion press embodying my improvements.

Fig. 2 is a top plan view thereof.

Fig. 3 shows a longitudinal vertical section of the press.

Fig. 4 is a view partly in section and 55 partly in elevation illustrating the manner in which the material is forced through the die.

Fig. 5 is an end elevation of the press.

Fig. 6 is a view partly in top plan and 60 partly in horizontal section, showing particularly the manner in which the cylindrical mass of material is inserted in the press cylinder.

Fig. 7 is a cross sectional view, illustrating 65 particularly the manner in which the press ram or plunger is moved sidewise into and out of position in line with the press cylinder.

The press is supported on heavy frame 70 pieces A and B tied together by rods C. The end frame A carries the cylinder D of the press which is formed with a cylindrical portion d and a tapered part d'. The frame B carries a cylinder E within 75 which operates the piston F to which is attached a platen G, supported and guided by two of the rods C. Hydraulic pressure is admitted to the cylinder E by the pipe e and serves to move the piston and platen in 80 one direction, i. e., toward the cylinder D. The piston and platen are moved in the opposite direction by a piston H carried by a cross head I which is connected with the platen G by rods G'. The piston H operates in a cylinder J to which hydraulic pressure is admitted through a pipe j.

It will be understood that when pressure is admitted at e, the piston F, platen G and piston H are moved in the same direction, 90 i. e., toward the cylinder D and that when pressure is admitted at j (the piston then being moved to its full extent in the cylinder J) the platen G, piston F and piston H will be returned to their normal positions. 95

The platen G carries an extrusion plunger K which operates in the cylinder D, but this plunger is movable sidewise on the platen for a purpose hereinafter described. For this purpose the plunger is formed with 100 a frame k which is guided by grooved flanges g on the platen. The plunger is moved back and forth sidewise by a screw L having a hand-wheel l and engaging the frame k of the plunger. The screw is supported in a lug g' rigid with the platen G.

The piston F is hollow and within this piston is a cylinder M, inclosing a piston N,

the rod *n* of which extends through the platen *G* and carries a head *n'*. Air is admitted to the opposite ends of the cylinder *M* by pipes *m*, *m'*. *T* indicates a table to receive the cylindrical mass of material to be operated upon. It is supported on two of the rods *C*.

While the press is especially intended to operate on asphalt, it may be made to operate on various kinds of plastic material or on other material, such as carbon. Asphalt is usually placed on the market in cases or sheaths made of sheet metal which can be readily removed from the cylindrical mass by cutting and stripping off the sheath. When the sheath is thus removed the cylindrical mass *X* may be placed on the table *T* and rolled into the position shown by dotted lines in Fig. 6, in line with the cylinder *D*. At this time the plunger *K* should be in the position shown in Fig. 6, *i. e.*, out of line with the cylinder. It is moved to this position by means of the screw *L*. At this time also the piston *N* is at the limit of its rear stroke. If now air be admitted by means of the pipe *m* to the cylinder *M*, the piston with its head *n'* will be moved toward the cylinder *D* and will move the cylindrical mass *X* into the cylinder in the manner indicated in Fig. 6, which figure shows the mass *X* moved partially into the cylinder, but by the continued movement of the piston the mass will be fully inserted into the portion *d* of said cylinder. It will be observed that the piston *N* is operated by compressed air; in this way a saving of hydraulic pressure is obtained although hydraulic pressure may be used for this purpose. After the mass *X* has been thus inserted air is admitted to the cylinder *M* through the pipe *m'*, air from the opposite end of the cylinder being exhausted in any suitable way. When air is thus admitted the piston *N* will be moved back to the position shown in Fig. 3, then the screw *L* may be operated to move the plunger *K* into position in front of the cylinder *D* and close to the end of the mass of material *X*. If, now, hydraulic pressure be admitted to the cylinder *E* through the pipe *e* the plunger *K* will be operated by hydraulic pressure to press the material gradually through a suitable die at the end of the cylinder *D*. It will be observed that by employing air pressure and a relatively light piston to insert the mass of material into the cylinder *D* such operation may be quickly performed, but when pressing the material through the die the greater hydraulic pressure is employed which operates more slowly and such relatively slow operation is, of course, desirable. After the mass of material has been forced through the die, hydraulic pressure may be admitted to the cylinder *J* through the pipe *j*. At this time of course the piston *H* is at the inner end

of its stroke and as this piston is connected in the manner before described with the platen *G* and therefore with the plunger *K*, said piston and plunger will be withdrawn from the extrusion cylinder. The platen and plunger may then be moved by means of the screw *L* to one side in the manner before described and another operation may be performed.

Any suitable die may be employed, but preferably the die is made in adjustable sections so as to vary the size of the strip or ribbon forced from the press. The die may be made adjustable to vary not only the thickness but also the width of the strip. I have illustrated, however, a form of die which has been found suitable for the purposes of this invention.

As shown more particularly in Figs. 3 and 5, the die comprises a stationary member, *R*, and a movable member *S*. The stationary member *R* is bolted to the end of the cylinder *D*. The movable or adjustable member *S* comprises a cross piece *s* and two downwardly extending arms *s'* which are inclosed in guides *r* projecting from the end of the cylinder. The die member *S* may be moved toward and from the member *R* by means of screw bolts *U*, carried by a flange *V* projecting from the end of the cylinder *D*.

The strips of material produced may be carried away in any suitable way; for instance, by an endless belt *W*, in the manner indicated in Fig. 4.

Experience has demonstrated that strips or ribbons of asphalt, carbon or other similar material may be much more expeditiously produced by a machine of the kind herein shown and described than by the old methods. No handling of material is necessary after the cylindrical mass is once placed in position in the press. The mass is quickly inserted in the extrusion cylinder and the hydraulic pressure on this mass may be properly controlled to produce the desired results.

I claim as my invention:—

1. Apparatus for forming strips of material, comprising an extrusion cylinder having a body portion and a tapered portion with a restricted discharge orifice, means moving longitudinally of the cylinder for moving a mass of material endwise into the body portion thereof, and other means for forcing the material into the tapered portion thereof and out through the restricted orifice.

2. Apparatus for forming strips of material, comprising an extrusion cylinder having a body portion and a tapered portion provided with a restricted discharge orifice having an adjustable die, means moving longitudinally of the cylinder for moving a mass of material endwise into the body portion of the cylinder and up to the tapered

portion thereof, and other means for forcing the material into the tapered portion thereof and out through the die.

3. Apparatus for forming strips of material, comprising an extrusion cylinder provided with a restricted discharge orifice, a table or support for a mass of material, fluid-operated means for moving the mass of material into the cylinder, and fluid-operated means for forcing the material through the discharge orifice.

4. Apparatus for forming strips of material, comprising an extrusion cylinder provided with a restricted discharge orifice, a table or support for the mass of material, means operated by air for moving the mass of material into the cylinder, and means operated by hydraulic pressure for forcing the material through the discharge orifice.

5. Apparatus for forming strips of material, comprising an extrusion cylinder, an air-operated piston for moving the mass of material into the cylinder, a plunger or ram for forcing the material through the discharge orifice, hydraulic means for operating said piston or ram, and means for moving the piston or ram sidewise into and out of position in line with the cylinder.

6. Apparatus for forming strips of material, comprising an extrusion cylinder provided with a restricted discharge opening equipped with a die, a table associated with the cylinder, fluid-operated means for moving a mass of material from the table into the cylinder, fluid-operated means for forcing the material through the die, and means for moving sidewise said last-mentioned fluid-operated means for the purpose specified.

7. Apparatus for forming strips of ma-

terial, comprising an extrusion cylinder having a restricted discharge orifice, a table associated with the cylinder for supporting a mass of material, a plunger or ram for forcing material through the die, a 45 platen on which said plunger or ram is supported, means for moving the ram sidewise in the platen into and out of position in line with the cylinder, a hydraulic cylinder associated with the platen, a piston carrying the 50 platen and which operates in said cylinder, a cylinder within said piston, a piston operating in said last-mentioned cylinder, a piston head connected with the piston and adapted to engage a mass of material and move it 55 into the extrusion cylinder, and means for operating said last-mentioned piston.

8. Apparatus for forming strips of material, comprising an extrusion cylinder provided with a restricted discharge orifice, a 60 table associated with said cylinder for supporting a mass of material, a plunger or ram for forcing material from the extrusion cylinder through the discharge orifice, a platen carrying said ram or plunger, means for 65 moving the ram sidewise in said platen, a piston supporting the platen, a cylinder in which said piston moves, hydraulic means for operating said piston, an air-operated piston within said first-mentioned piston, a 70 piston rod provided with a head which is adapted to engage the mass of material and move it into the extrusion cylinder, means for admitting compressed air to operate said last-mentioned piston, and means for returning the ram to a position withdrawn from the extrusion cylinder. 75

In testimony whereof I have hereunto subscribed my name.

FRANCIS E. STEVENSON.
